Patented Apr. 17, 1923.

1,452,006

UNITED STATES PATENT OFFICE.

HARRY STEHMANN, OF BERLIN-HOHENSCHONHAUSEN, GERMANY.

GRATE FOR SHAFT FURNACES.

Application filed August 1, 1919. Serial No. 314,786.

(GRANTED UNDER THE PROVISIONS OF THE ACT OF MARCH 3, 1921, 41 STAT. L., 1313.)

To all whom it may concern:

Be it known that I, HARRY STEHMANN, engineer, a citizen of the German State and resident of Berlin-Hohenschonhausen, Germany, have invented certain new and useful Improvements in Grates for Shaft Furnaces (for which applications for patents have been filed in Germany, 7 July, 1914, 10 Feby., 1915, and 3 Nov., 1915; in Austria, 8 July, 1915; in Hungary, 9 July, 1915, and 22 Jany., 1916; in Switzerland, 24 October, 1918; in Denmark, 24 October, 1918; in Norway, 29 October, 1918; in Sweden, 30 October, 1918; in Spain, 26 November, 1918; 15 and in Belgium 25 November, 1918) and I do hereby declare the following to be a full, clear, and exact description of the invention, such as will enable others skilled in the art to which it appertains to make and use the 20 same, reference being had to the accompanying drawings, and to letters or figures of reference marked thereon, which form a part of this specification.

The problem met in sintering shaft kilns, such as for sintering magnesite, cement and the like, where fusion of the mass treated is not contemplated, has been the removal of the sintered product from below the sintering zone in a constant and uniform manner.

30 The sinter block below the sintering zone should descend in the kiln to maintain the sintering zone above the block or mass at about a stationary height notwithstanding the constant removal of sintered product at the bottom, and a constant supply of raw material at the top of the kiln.

I have discovered that if the entire kiln content is supported over the entire kiln cross section at the bottom on crushing rolls, that the sintered base of the charge will be uniformly broken away on its under surface and discharged, the weight of the charge forcing the sintered mass continually against the rolls. This insures a uniform breaking away of the sinter at the bottom of the charge over the whole area; the charge sinks uniformly and the sintering zone remains about stationary in position without being extended upwardly or downwardly, or both, as is often the case when the breaking away of the sinter does not extend over the whole cross-sectional area of the kiln.

I have thus solved one of the most troublesome problems in the operation of sintering 55 shaft kilns.

In the accompanying drawing I have illustrated a mechanism for effecting the result desired in a simple and efficacious manner.

Figure 1 is a vertical section of the lower part of a shaft kiln embodying my invention.

Fig. 2 is a plan view of Fig. 1, being a section on line A—B of Figure 1.

Fig. 3 is a cross section of one form of crushing roll differing from that shown in Fig. 1.

Fig. 4 is an elevation of Fig. 3.

In the particular instance illustrated the 70 kiln has in the bottom of its shaft four co-operating crushing rolls *a* mounted in shafts *h* extending through the masonry of the kiln, and each shaft has on it, outside the kiln, a gear wheel, *c*¹, *c*², *c*³, *c*⁴. The gear 75 wheels *c*¹ and *c*² intermesh, and the gear wheels *c*³ and *c*⁴ intermesh. The gear wheels *c*² and *c*³ are each positively driven by a worm *e*, and the two worms *e* are mounted on a shaft that is provided with a pinion *d* 80 which in turn is driven by a worm on a shaft provided with a driving pulley.

Instead of making the crushing roll solid and providing it with peripheral crushing teeth as in Fig. 1, it may be constructed hollow, as in Figs. 3 and 4, in which case the shaft *h* is provided with spiders *i* having openings *m* through them, with spaced bars *k* extending parallel to the shaft across the spiders, so that the sinter may pass through as well as between the crushing rolls.

Below the crushing rolls *a* I prefer to mount a grate-like concave *f* generally conforming to the under surface of the crushing roll assembly, and with which the rolls *a* 95 co-operate to again crush the sinter after it has passed between or between and through the rolls; and below the concave *f* is a discharge hopper or bin *g*.

I claim—

1. The combination with a kiln shaft, of a series of continuously rotating co-operating clinker-removing crushing rolls extending over the whole cross sectional area of the kiln and supporting the kiln charge.
2. The combination with a shaft kiln; of

a series of co-operating clinker removing crushing rolls extending over the cross-sectional area of the kiln, and a grinding concave below said rolls and co-operating therewith.

3. The combination with a shaft kiln; of a series of co-operating clinker removing crushing rolls extending over the cross-sectional area of the kiln, a grinding concave 10 below said rolls and co-operating therewith and means to continuously rotate said rolls.

4. A shaft kiln having a series of co-operating crushing rolls extending over the cross-sectional area of the kiln and supporting 15 the kiln charge, and a grate-like grinding concave below and co-operating with said rolls.

5. A shaft kiln having a series of co-operating crushing rolls extending over the cross-sectional area of the kiln and supporting 20 the kiln charge, a grate-like grinding concave below and co-operating with said

rolls, and means to continuously rotate said rolls.

6. A shaft kiln having a series of co-operating crushing rolls extending over the entire cross-section of the kiln and supporting 25 the charge, said rolls each comprising a shaft, spiders thereon and bars extending across said spiders.

7. A shaft kiln having a series of co-operating crushing rolls extending over the entire cross-section of the kiln and supporting 30 the charge, said rolls each comprising a shaft, spiders thereon and bars extending across said spiders, and a grinding concave 35 in crushing relation to said rolls.

In testimony that I claim the foregoing as my invention, I have signed my name in presence of two subscribing witnesses.

HARRY STEHMANN.
